FIG. 3B

FIG. 3C

Fig. 1 is a full-scale fragmentary plan view of a typical portion of the plastic coated sheet material embodying our new design, specifically the portion enclosed within the dot and dash lines appearing in the upper left corner of Fig. 3A;

Fig. 2 is an enlarged vertical sectional view of the fragment of plastic coated sheet material of Fig. 1 taken along the line 2—2; and

Figs. 3A, 3B and 3C, taken together by placing the lines A—A' and B—B' in juxtaposition, constitute a plan view of the plastic coated sheet material of the invention, showing a complete design unit with extension beyond the unit boundaries as indicated by the marks at the edges of the figures.

We claim:

The ornamental design for a plastic coated sheet material, substantially as shown and described.
